UNITED STATES PATENT OFFICE.

MAX BARTHOLDY, OF ESSEN, GERMANY, ASSIGNOR TO FRIED. KRUPP AKTIEN-
GESELLSCHAFT, OF ESSEN-ON-THE-RUHR, GERMANY.

GAUGE.

Application filed March 10, 1922. Serial No. 542,772.

To all whom it may concern:

Be it known that I, MAX BARTHOLDY, residing at Essen, Germany, a citizen of the German Republic, have invented a certain 5 new and useful Improvement in a Gauge, of which the following is a specification.

This invention relates to gauges of the kind in which the gauge-body carries a bolt which has a gaging surface and is axially 10 adjustable but held against rotation in the gauge-body.

In a known gauge of this kind the gaging bolt is shiftable axially by means of a screw which, in its turn, is mounted non-shiftably 15 in the gauge body and meshes with an internally threaded bore of the gaging bolt. With this known construction, the bearing surface of the gaging bolt is of course considerably decreased, and consequently the 20 guiding of the bolt grows worse the more the bolt extends beyond the gauge-body. Besides, such arrangement has the disadvantage that the diameter of the gaging bolt is bound to a certain minimum measure, as 25 otherwise the screw engaging the bolt would have to be made of too small dimensions. These disadvantages are obviated by the construction of the gauge according to the present invention.

30 Besides this, the invention has for its object to provide a very compact gauge of the said type, the adjustment of which to a standard measure can be effected accurately and simply within a short time.

35 With these ends in view the invention consists in the arrangement, construction and combination of the parts to be herein described and particularly pointed out in the appended claim.

40 In the drawings:

Fig. 1 is a view, partly in section, of a snap-gauge constructed in accordance with the invention;

Fig. 2 is a transverse section on the line 45 2-2 of Fig. 1, seen from the left.

Referring now to the drawings, in which similar characters of reference indicate corresponding parts, A designates the frame of the gauge. One end of the frame A carries 50 a housing A¹ in which a pin C is shiftable mounted which is adapted to actuate the pointer B of an indicator B-a². Mounted in front of the pin C is a ball D adapted to roll on a stationary oblique face a³ and 55 projecting somewhat from the housing A¹.

The ball D constitutes the movable gaging member of the gauge. The other end of the frame A which is opposite to the ball D, forms a socket-like enlargement a⁴ in which a bolt E is mounted which forms the fixed 60 but adjustable gaging member of the gauge.

The bolt E has a cylindrical portion which is provided with millimeter graduations e¹ which correspond to the distance between the bolt E and the ball D when the latter is in 65 a definite position. The bolt E is surrounded by a sleeve F which is mounted for rotation in the socket a⁴ and which is provided with longitudinal slots f¹. The end of the sleeve F which is remote from the gaging surface of 70 the bolt E, is provided with an internal screw thread which is in engagement with a corresponding externally threaded portion e² of the bolt E, so that an adjustable connection is established between the parts E and F. 75 The other end of the sleeve F, which is situated adjacent to the gaging surface of the bolt E and projects beyond the socket a⁴, is provided with a collar f² preferably knurled. This collar f² tapers into a cone 80 f³ forming a sharp reading-off edge f⁴. The collar f² is caused to abut against the socket a⁴ from the exterior by the action of a spring G one end of which bears against a disk e³ which is fastened to the bolt E, 85 while its other end bears against a split clamping ring H surrounding the sleeve F and abutting against an inwardly projecting annular flange a⁵ of the socket a⁴. The disk e³ possesses a projection e⁴ which engages a longitudinal groove a⁶ of the socket a⁴ so that the bolt E is held against rotation. The clamping ring H is provided with two recesses h¹ constituting two stop-faces h² and 90 h³, respectively, (Fig. 2). The wall of the 95 socket a⁴ is provided with aligned screw-threaded holes receiving screws J and K, the screws J having a knurled head and being adjustable in the hole receiving it. Its inner end bears against the stop-face h², while 100 the screw K is stationary with relation to the socket a⁴ and has its inner end bearing against the stop-face h¹. When using the gauge, the screw J is tightened so as to cause the clamping ring H to press the slotted 105 sleeve F tightly around the bolt E, whereby any shifting of the bolt E as well as of the sleeve F is rendered impossible. The outer end of the socket-like enlargement a⁴ is closed by a cap a⁷ screw threaded thereon 110

whereby access may be had to the interior of the enlargement a^4 by removing this cap a^7 .

In case a body should be tested by means 5 of the gauge described, the said body is introduced between the ball D and the bolt E. If the respective body has at least approximately the exact measure, the ball D will be slightly pressed back into the housing A¹ so that it will roll up the oblique face a^8 and cause the pin C to be shifted in the direction of the arrow x. The shifting of the pin C will produce a deflection of the 10 pointer B which indicates, whether the body to be tested possesses a sufficiently accurate 15 measure. With the position of the bolt E illustrated in Fig. 1, the gauge is adapted for testing bodies the length or diameter of which should be 80 mm. for example. If 20 bodies of smaller dimension, for example 75 mm., should be tested, the knurled screw, and therewith the clamping ring H, are loosened, whereupon the sleeve F will be rotated. This rotation will cause an axial 25 shifting of the bolt E, and is continued until the division mark 75 of the graduation e^1 will come to meet the reading-off edge f^4 . It is then examined, by the aid of a standard 30 caliper-pin, whether the adjusted measure is exactly equal to 75 mm. If the measure is found to be accurate, the pointer B will have to take the position indicating zero on the scale a^2 , otherwise the bolt E will have to be adjusted more accurately. The screw 35 J is then tightened, and the gauge is ready for use again. Any play at the screw-

threads between the bolt E and the sleeve F is excluded by the action of the spring G, so that any shifting of the bolt E after its adjustment, before the sleeve F is clamped to 40 the bolt E by means of the clamping ring H, is prevented.

It will be evident from the foregoing description that the adjustment of the gauge can be efficiently and reliably performed 45 within a very short time. Besides, the construction of the gauge is simple and compact; nevertheless, the mounting of the bolt E in the socket a^4 or sleeve F, respectively, is such as to secure a uniformly good guiding of the bolt E in every position. The diameter of the bolt E is not subject to any 50 limitations.

Claim:

A gauge, comprising a frame carrying oppositely disposed spaced gauge points one of which is formed by a graduated bolt which is mounted for actual shifting motion in the 55 said frame and which is provided with means for locking the bolt against rotation, 60 said graduated bolt having an externally threaded portion, an internally threaded sleeve rotatably mounted in the frame of the gauge, said sleeve surrounding the graduated bolt and meshing with the threaded 65 portion of the same, and means for locking the said sleeve against shifting motion.

The foregoing specification signed at Essen, Germany, this 3rd day of February, 1922.

MAX BARTHOLDY.

Certificate of Correction.

It is hereby certified that in Letters Patent No. 1,448,373, granted March 13, 1923, upon the application of Max Bartholdy, of Essen, Germany, for an improvement in "Gauges," an error appears in the printed specification requiring correction as follows: Page 2, line 58, the claim, for the word "actual" read *axial*; and that the said Letters Patent should be read with this correction therein that the same may conform to the record of the case in the Patent Office.

Signed and sealed this 3d day of April, A. D., 1923.

[**SEAL.**]

KARL FENNING,
Acting Commissioner of Patents.
